CLAIM

The ornamental design for a tire cover, as shown.

DESCRIPTION

FIG. 1 illustrates a perspective view of a tire cover, the broken lines illustrate environmental structure in the drawing and is not part of the design sought to be patented.

FIG. 2 illustrates a front view of a tire cover, the broken lines illustrate environmental structure in the drawing and is not part of the design sought to be patented.

FIG. 3 illustrates a rear view of a tire cover, the broken lines illustrate environmental structure in the drawing and is not part of the design sought to be patented.

FIG. 4 illustrates top and bottom view of a tire cover, the broken lines illustrate environmental structure in the drawing and is not part of the design sought to be patented.

FIG. 5 illustrates left and right side view of a tire cover, the broken lines illustrate environmental structure in the drawing and is not part of the design sought to be patented.

FIG. 6 illustrates rear perspective view of a tire cover, the broken lines illustrate environmental structure in the drawing and is not part of the design sought to be patented; and,

FIG. 7 illustrates a cross-section of a view of a tire cover, the broken lines illustrate environmental structure in the drawing and is not part of the design sought to be patented.

1 Claim, 6 Drawing Sheets
